UNITED STATES PATENT OFFICE.

GEORGE KOHLMAYER, OF COLLEGE POINT, NEW YORK, ASSIGNOR TO AMERICAN HARD RUBBER COMPANY, OF HEMPSTEAD, NEW YORK.

DESIGN FOR A COMB.

Application filed August 27, 1926. Serial No. 18,888. Term of patent 14 years.

To all whom it may concern:

Be it known that I, GEORGE KOHLMAYER, a citizen of the United States, residing at College Point, in the county of Queens and State of New York, have invented a new, original, and ornamental Design for Combs, of which the following is a specification, reference being had to the accompanying drawing, forming part thereof.

The figure is a front view of the comb, showing my new design the dominant feature of which is the effect of the faceting at the base of the teeth.

I claim:

The ornamental design for a comb, as shown and described.

GEORGE KOHLMAYER.
